(57) **CLAIM**

The ornamental design for a dispensing cap, as shown and described.

DESCRIPTION

FIG. 1 is a perspective view from above of a dispensing cap showing my new design, with the nozzle cover of the dispensing cap positioned on the nozzle of the dispensing cap;

FIG. 2 is a perspective view from above of the dispensing cap of FIG. 1 with the nozzle cover of the dispensing cap removed from the nozzle of the dispensing cap.

FIG. 3 is a perspective view from below of the dispensing cap of FIG. 1 with the nozzle cover of the dispensing cap positioned on the nozzle of the dispensing cap.

FIG. 4 is a side view of the dispensing cap of FIG. 1.

FIG. 5 is a side view of the dispensing cap shown in FIG. 2.

FIG. 6 is a top view of the dispensing cap of FIG. 1.

FIG. 7 is a bottom view of the dispensing cap of FIG. 1.

FIG. 8 is a front view of the dispensing cap of FIG. 5; and, FIG. 9 is a rear view of the dispensing cap of FIG. 4.
